ATTORNEY

UNITED STATES PATENT OFFICE

134,975

DESIGN FOR A PIN OR SIMILAR ARTICLE

Sam Favari, Weirton, W. Va.

Application April 24, 1942, Serial No. 106,685

Term of patent 3½ years

To all whom it may concern:

Be it known that Sam Favari, a citizen of the United States of America, residing at Weirton, in the county of Hancock and State of West Virginia, has invented a new, original, and ornamental Design for a Pin or Similar Article, of which the following is a specification, reference being had to the accompanying drawing, forming part thereof.

Fig. 1 is a front view of a pin embodying my new design.

Fig. 2 is a plan view thereof.

I claim:

The ornamental design for a pin or similar article, as shown.

SAM FAVARI,
